UNITED STATES PATENT OFFICE.

ANSEL N. KELLOGG, OF CHICAGO, ILLINOIS.

GAME APPARATUS.

SPECIFICATION forming part of Letters Patent No. 230,947, dated August 10, 1880.

Application filed April 3, 1880. (No model.)

To all whom it may concern:

Be it known that I, ANSEL N. KELLOGG, of Chicago, in the county of Cook and State of Illinois, have invented certain new and useful 5 Improvements in Game Apparatus, of which the following is a specification.

My invention relates to improvements in apparatus for playing games; and the same consists in a triangular-shaped box frame or 10 case provided with a number of small movable triangular blocks, properly designated by number, adapted to be arranged in different orders by sliding or moving the same about the case.

15 In the accompanying drawings, which form a part of this specification, Figure 1 is a plan of a device embodying my invention. Fig. 2 is a side view of the same, the cover for the case being indicated by the broken line. Fig. 3 20 is a section of the same on the line $x-x$ of Fig. 1. Fig. 4 is a plan of one of the movable triangular blocks; and Fig. 5 is a side view of the same.

In said drawings similar letters of reference 25 indicate like parts throughout all the figures.

A represents the bottom of the triangular case or box, and B the sides of the same. The sides B of the box should be made of about the same height as the thickness of the blocks C. 30 The box may be made of different sizes, depending, however, upon the size and number of the blocks C, and it may be constructed in the form of an equilateral triangle, as shown in the drawings, or it may be made in the form 35 of a right-angle triangle, or other shaped triangle; but I prefer to make it in the form of an equilateral triangle, as that presents a more regular figure.

C are the triangular movable blocks, 40 made of such size that 9 16 25, or other square number of them, just fill the interior of the triangular box with such snugness as to permit of the blocks being readily slid or moved into different positions when two or more 45 of the blocks are removed from the box, but not to permit of their being turned around. The blocks C are all of the same size, and are similar in shape to the triangular box—that is to say, if the box is an equilateral triangle the blocks are also equilateral trian-

gles, whose sides are one-third, one-fourth, one-fifth the length of the side of the box, and if the box is in the form of a right-angle triangle the blocks are similar right-angle triangles.

The tops of the blocks are marked or stamped with numbers from 1 to 9, 16, or 25, consecutively, according to the number of blocks employed; or they may be marked with letters, which may be arranged to spell or read different 60 words or sentences; or they may be otherwise designated by appropriate characters, and the game consist, as before, in moving them into certain orders or positions.

The top corners of the blocks are cut or beveled off somewhat to afford facility in moving them.

The central block, which in the drawings is marked 7, is provided with a hole, D, for the insertion of a pin or plug, d, which fits in a 70 corresponding hole, D', in the bottom of the box, for the purpose of securing said block in position and rendering the same immovable when desired. The same feature may be used with others of the blocks, if desired.

The boxes may be made to contain any square number of blocks, such as 9 16 25; but a box provided, for instance, with sixteen blocks, may be used as a box containing nine blocks by leaving the blocks from 10 to 16 in 80 position and considering them as immovable in the box, and so also with a box containing twenty-five blocks may be used as a box containing sixteen or nine blocks.

In playing games which consist in arranging the blocks in particular orders by sliding them from one position to another, two of the blocks are to be removed from the box, the blocks numbered 15 and 16, for instance, if the box used is one containing sixteen blocks.

90 My invention is adapted to be used in playing a variety of interesting games, either with all the blocks movable or with some one or more of them fixed, as described; and it is also adapted to be used in those games which consist in arranging the blocks so that the sums of their numbers in all directions shall be the same.

I am aware that square boxes containing sixteen square blocks have been used hereto- 100

fore, commonly known as the "Fifteen Puzzle." I disclaim this as no part of my invention.

The triangular disposition of the blocks renders the moves in the game more complicated and difficult, while at the same time there is no impossibility of solution with free blocks.

The feature of fastening one or more of the blocks may be employed with a square box or case and square blocks; but I prefer to employ the triangular form.

I claim—

The combination of a triangular box or frame with movable blocks shaped similarly to the box, marked with numbers thereon, and adapted to be arranged in different orders by sliding or moving them about in the box, substantially as set forth.

ANSEL N. KELLOGG.
